NONREEMPTYING BOTTLE

Lester L. Lewis, Cabot, Pa., assignor to Lew-
rith Receptacle Corporation of Pennsylvania,
Pittsburgh, Pa.

Application August 12, 1937, Serial No. 158,789

2 Claims. (Cl. 215—18)

This invention relates to improvements in containers of the type designed to prevent misrepresentation regarding the contents and as such is in the form of a non-refillable receptacle.

In the art to which the present invention relates efforts have been popularly made to prevent the refilling of receptacles, such as bottles, in order to avoid the possibility of either the offering of a spurious substitute or the illegal marketing of a refilled bottle or other receptacle. Quite extensive efforts have, accordingly, been exerted in the direction of preventing the refilling of bottles and like receptacles, and containers and such receptacles have come to be commonly known as non-refillable bottles even though it is well known that it is practically impossible to actually prevent refilling because of the advance that has been made in the welding of glass by which it is possible to either remove the bottom of a glass receptacle and re-weld it in a manner not observable, or it is possible to drill through an appropriate part of the wall of the receptacle and after filling weld the opening thus formed in a not readily detectable manner.

It is, therefore, not sufficient to provide means to prevent liquid being introduced into a bottle or other receptacle through the opening from which liquid is intended to be discharged. Accordingly, the present invention provides the novel combination of means for preventing the refilling of a receptacle through the port or opening through which its contents is intended to be regularly discharged with means for preventing discharge of the contents of the same receptacle, if the receptacle be refilled by any means after it shall have been completely discharged through the regular discharge opening.

In other words, the novel idea of the present invention is directed to preventing discharge of the contents of a receptacle after the receptacle has once been emptied rather than, or supplemental to, the effort to prevent refilling, so that the present invention may be tersely described as a combination of parts providing a non-re-emptyable receptacle.

With this and more detailed objects in view as will in part hereinafter become apparent and in part be stated, the invention includes means in combination with a receptacle, to control the once emptying of the contents of a filled receptacle, and thereafter prevents a second emptying thereof, unless accompanied by such breakage as to plainly indicate the fact of the second filling.

The invention further comprises a control of

the measuring type for governing the discharge of the contents of a receptacle and means cooperating therewith for precluding further discharge after an amount has been discharged substantially equal to the capacity of the receptacle.

The invention also includes in greater detail in such an arrangement means for preventing repetition of the measuring operation or restoration thereof to a condition enabling such repetition.

The invention also comprises certain other novel constructions, combinations, and arrangements of parts as subsequently specified and claimed.

In the drawings:

Figure 1 is a sectional elevation of a structure embodying the features of the present invention, parts of the receptacle being broken away for the saving of space;

Figure 2 is a complete section through the said parts taken on substantially the same plane as the plane of the section of Figure 1;

Figures 3, 4, 5, and 6 are horizontal cross sections taken substantially on the planes indicated respectively by lines 3—3, 4—4, 5—5 and 6—6 of Figure 2 and looking downward, the parts being in the non-discharging position or position for filling the discharge tube;

Figures 7, 8, and 9 are similar cross sections on the same planes as seen respectively in Figures 3, 4, and 5, with the parts set to the discharge position;

Figure 10 is a view similar to Figure 6 of a slightly modified embodiment;

Figure 11 is a view similar to Figure 2 of another modification;

Figures 12, 13, and 14 are transverse, horizontal sections taken respectively on the planes indicated by lines 12—12, 13—13, and 14—14 of Figure 11; and

Figure 15 is a fragmentary central vertical section through a modified form of the bottle.

Referring to the drawings by numerals, I indicates a bottle or other container or receptacle having an appropriate discharge port or orifice 2 usually delineated by a neck or tubular extension 2 of the receptacle 1. A discharge outlet nozzle 3 preferably leads laterally from the tubular extension 2 for directing liquid discharged from the neck 2. Seated within the neck 2 and closing the same is a stopper controlling the discharge of liquid from container 1 and precluding refilling of the container through the said neck. The said stopper consists of a tubular housing or jacket 4 arranged within the neck 2 and snugly

5

fitting the same throughout a substantial portion of its length from its outer end inward. The passageway of the neck 2 is tapered preferably from its outer or upper end toward its inner end or end integral with the receptacle 1, and the taper preferably extends throughout that portion snugly engaged by the housing 4, as clearly seen in Figure 1, and the housing is correspondingly tapered through that portion of the housing which snugly engages the surrounding wall of the neck 2. Of course, the extent of such engagement is susceptible of variation, but it is preferable that the same shall extend past the outlet nozzle 3 and a sufficient distance at each side of the same to insure against the possibility of leakage either from the bottle 1 to the nozzle 3 or conversely.

Below or inward of the tapered portion of the neck 2 with which the housing 4 snugly engages, the neck is provided with an enlargement affording an annular chamber 6 surrounding the inner or lower portion of the housing 4. The housing or jacket 4 is constructed to be locked to the neck 2 so that, after insertion of the housing, it can not be removed. This can be accomplished in any of various ways by the provision of an appropriate elastic or resilient detent adapted to be sprung into place but incapable of being removed without breaking some part of the assembled structure. Such a detent is shown in the drawings and consists of a split washer 7 seated in an annular groove 8 in the housing or jacket 4 and also seated in an encircling groove 9 formed in the inner surface portion of the neck 2. Obviously, the split washer 7 will, in operation, be sprung into the groove 8 and then the housing or jacket 4 inserted longitudinally in the neck 2 until the ring 7 reaches the groove 9 where it will spring out into a seated position in the groove 9 while having a substantial portion still remaining in the groove 8. Thus, the housing or jacket 4 can not be removed from the bottle neck without breakage of the parts.

Within the housing 4 is arranged a shell 10 which, because of its function, may be considered a discharge tube or measuring receptacle. The shell 10 is snugly nested in and extends for the greater part of the length of the housing or jacket 4.

A port of slot-like form 11 is provided through the wall of jacket or housing 4 in register with the nozzle 3, and the lower portion of the housing 4 is provided with a number of slots or ports 12 opening into the chamber 6. It follows that if the shell 10 were not present liquid could flow readily from the container 1 through the slots 12 and either out through the slot 11 or through the open end of the jacket or housing 4; but the shell 10 closes the outer end of housing 4 and at times closes the slot 11; that is, when the parts are in the non-discharging position as seen in Figures 2 and 3.

The shell 10 is, however, provided with a series of ports or slots 13 in the zone of the slot 11 and another series of slots or ports 14 in the zone of the slots 12. The slots 14, however, are distributed angularly about the shell 10 to be spaced approximately 45° from an alinement with the slot 13. The relative location of the slots 13 with respect to the slots 14 will be readily apparent from a comparison of Figures 7 and 9, and is also seen in Figure 2. Thus, when the slots 14 are in register with the slots 12, as seen in Figures 2 and 5, the slots 13 will be out of reg-

ister with the slot 11, and, on the other hand, when any one of the slots 13 is in register with the slot 11 the several slots 14 will be out of register with all of the slots 12, as seen in Figure 9. Thus, to pour liquid from the container 1 through the spout or nozzle 3, the liquid must first enter the discharge tube or shell 10 through the slots 14 from the slots 12, and then the shell must be advanced angularly approximately 45° until one of the slots 13 arrives at registration with the slot 11, whereby the supply from the chamber 6 is cut off from the discharge tube 10, and the contents of that tube alone can be discharged through the nozzle 3.

To control the possible relationships of the discharge tube or shell 10 and the housing 4, the housing 4 has its lower end closed by a preferably integral solid portion 15 which is formed with an axial internally-threaded passageway 16 through which is threaded a stem 17 carried by and preferably formed integral with the bottom 18 of the discharge tube or shell 10. The bottom 18 seals the lower end of the tube 10.

The upper end of the shell 10 is preferably closed by an appropriate cover or cap 19 that is formed integral with or otherwise welded or sealed to the walls of the shell 10 for sealing the chamber thereof against access. The threaded stem 17 in addition to having the regular thread spiral 20 is formed with longitudinal grooves 21 extending along the stem and intersecting the several helices of the thread 20, so that the remaining portions of the thread 20 present a series of exposed ends alined along the several grooves 21. A pawl 22 is pivoted, as at 25, to the lower extremity of the housing 4 in position to have its free end engage in any one of the several grooves 21, as best seen in Figure 6; and the spring 26 stresses the pawl into such engaging position. A cap 23 is fixed to the lower 40 end of the housing 4, surrounds the stem 17, and encloses the pawl 22.

To the lower end of the stem 17 is fixed a stop 24 which is merely an enlargement of knob or button-like form located to come in contact 45 with the lower end of the cap 23 and thereby prevent further threading movement of the stem 17 upward.

The several parts, with the exception of the spring washer 7 and the pivot for the pawl 22, 50 are formed of glass or other appropriate ceramic material, and so far as possible each part is either originally formed integral or glass welded. For instance, the cap or cover 19 is die cast integral with the shell 10, and the closure or head 55 of stem 17 is either formed integral with or welded to the surrounding walls of the shell 10. It is preferable to have either the part 19 or the part 18 originally formed separate and subsequently anchored to the shell 10 for convenience 60 of manufacture; but these parts, however originally made, are connected in the course of assembly to be as nearly as possible integral so that access can not be had or improper use made of the parts without such injury thereto as to indicate the lack of genuineness of an altered product. The stem 17, which is also of glass, has the knob or stop 24 also welded onto its lower end. Of course, where the difficulties of welding preclude, cementing may be resorted to, but the welding 70 is preferred as more effectively dependable to avoid undisclosed tampering.

It will be noted, as seen in Figure 6, that the engaging end portion of the pawl 22 is shaped to present an abutting shoulder to the thread pro- 75

jections or ends along each of the grooves 21, while the pawl presents a rounded portion in the opposite direction, so that the stem 17 is free to be rotated in a contra-clockwise direction. During such rotation, the pawl 22 successively swings upon its pivot out of one of the grooves 21 against the pressure of spring 26, rides across the thread segments, and drops into the next groove 21, and so on, as the stem 23 is rotated. The thread 20 is of the righthand variety so that, should the stem 17 be revolved clockwise instead of contra-clockwise, the stem would be caused, owing to its thread engagement with the base or bottom 15 of housing 4, to move inward or downward; but the presence of the pawl 22 and its action with respect to the thread segments precludes the possibility of any such movement. Pawl 22, therefore, permits only such rotation of the stem 17 as will cause the stem to travel outward through the bottom 15 of housing 4.

Of course, when the receptacle of bottle 1 is first filled and the housing 4 and its carried parts are inserted, the stem 17 will be in its lowermost position, and the stop 24 is located to contact with the cap 23 in timed relation to the exhaustion of the contents of the bottle to avoid any appreciable further movement of the parts after exhaustion of the contents of the receptacle 1. Furthermore, the stop 24 is located with respect to the threads such that, when the pawl 22 drops into the last groove 21 which it can engage as the stop 24 contacts, the cap 23 and slot 13 will preferably be out of alignment with the slot 11. Of course, the grooves 21 are located relative to the location of the slots 13, 14 and 12 such that, when the pawl 22 engages any one of the grooves 21 where the slots 13 and 11 are in registration, the next step bringing the pawl into engagement with the next groove 21, causes the shell 10 to have such angular advance as to bring the slots 14 and 12 into registration, so that the slot 11 is closed, and these successive relationships are maintained by the successive steps represented by the succeeding grooves 21 in their relation to pawl 22 as the stem 17 is revolved.

To avoid delay in the rate of discharge from the discharge tube or shell 10, it is desirable to provide means for admitting air to the interior of the shell 10 when liquid is to be delivered therefrom. For this purpose, a preferably minute port 27 is formed through the neck 2 and through the housing 4, preferably at a point diametrically opposite from the nozzle 3. The shell 10 is provided in line with each of the slots 13 with a series of miniature ports 28 alined vertically and spaced apart equal to the longitudinal travel of the shell 10 incident to a complete rotation or movement thereof through 360°. In other words, the distance from one port 28 to the next lower port 28 of the several rows of ports below the several slots 13 is equal to the spacing of the thread helices of thread 20. Thus, when a slot 13 comes into register with slot 11, one of the ports 28 comes into register with port 27 and allows sufficient admission of air to permit free discharge of the contents of the discharge tube 10.

The operation should be obvious from the foregoing, but may be briefly stated, after the parts have been assembled with the receptacle 1 filled and the closure 19 resting on the upper end of housing 4, or substantially so, to consist of turning the closure 19, which thus serves as a knob, that is in the direction which is contra-clockwise. The first turning movement will result in the pawl 22 rising over one of the thread segments

and dropping into the next groove 21. The operator hearing the resulting sound will discontinue movement of the shell 10 and either invert, or sufficiently nearly invert, the bottle or receptacle 1 to enable liquid to flow along the chamber 6 through the slots 12 and 14 and into the discharge tube 10 until it is filled. The operator then turns the knob 19 for one more click which cuts off the registration of slots 14 with slots 12, and brings a slot 13 into register with the slot 11, and at the same time brings a port 28 into register with the port 27. The contents of the discharge tube may thus be freely discharged through the spout or nozzle 3. This operation may be repeated step by step until the entire contents of the bottle has been discharged, and at that time the stop 24 will either be in contact with the cap 23 or sufficiently near to the cap to preclude any appreciable introduction or removal of liquid.

It should be understood that should an operator choose at any time he can, when a slot 13 is in register with a slot 11, pour liquid into the spout 3 sufficient for filling the discharge tube 10, and then by turning the tube 10 to the next notch and thus bringing the slots 12 and 14 into register, cause the thus introduced liquid to enter the receptacle 1. Such an introduction of liquid, however, can not be of any profit to the operator, since he has lost just that much in the longitudinal thrust of the tube 10, which thrust is the controlling factor in emptying the receptacle. When the shell or tube 10 has reached its maximum limit of longitudinal thrust there is nothing that can be done to allow the contained liquid to escape, if there be any contained liquid. Accordingly, the length of the stem 17 is preferably slightly longer and the number of available notches over which the pawl 22 may travel slightly greater than that required for the actual complete emptying of the receptacle 1, so as to insure against accidental movement of the operating knob 19 having the effect of rendering some of the original contents inaccessible.

After the bottle has once been completely emptied and the discharge tube or shell 10 has reached the limit of its longitudinal travel from which it can not be backed off, any filling of the bottle as by the removal of the bottom and the re-welding of it will be of no avail, since it is not possible, having once emptied a bottle, to re-empty it. Accordingly, the present invention involves not only a non-refillable receptacle in the sense in which that term is generally accepted, but also includes the capacity to resist re-emptying. Thus, refilling is effectively discouraged.

By these means not only is the public assured of the genuineness of the original contents, but the possibility of marketing a receptacle bearing a revenue stamp that has once been used is destroyed.

The matter of effectiveness of construction of course possesses the possibility of some variation, but in order to insure the best results it is desirable wherever there is not an actual glass weld between two glass portions to provide a fusible cement between the separate parts that are brought together and to fuse the cement after the application. For instance, the housing 4 is preferably coated with a fusible cement especially at its outer end portion, which cement is fused after the insertion of the housing 4 in the neck 2. The relatively tapered contacting faces of the two parts insures a tight joint in the first place, and the fused cement precludes possibility of separation in addition to the capacity of the washer 7.

Where the operating knob or closure 19 is formed separately from and connected to the shell 10, glass fusing is preferred, or in lieu thereof the part 19 may have a shank extending into the upper end portion of the shell 10 and fixed thereto by the use of fusible cement fused after the insertion. The part 18 is shown as having been inserted into and closing the lower end of the shell 10, and when thus made separate and introduced is similarly fused and anchored so as to preclude possibility of separation during use. Likewise, the knob or stop 24 is effectively either glass fused or cemented with a fusing cement and fused to the stem 17. The cap 23 is similarly fixed to the lower end of the housing 4. It is to be noted that the cap 23 has an opening for the passage of the stem 17 only very slightly larger than the overall diameter of the thread 20 so that an instrument can not be introduced to release the pawl 22, even if the bottom of the receptacle 1 is removed before the stop 24 has reached its seated position against the cap 23.

In Figure 10, the structure is the same as that above described with the exception of the pawl which is seen as a spring 29. The other parts being identical with those above described bear the same reference numerals and the same description applies, except that the spring pawl 29 is welded at 30 in the material of the cap 23 instead of being pivoted to the lower end of the discharge tube.

In Figures 11 to 14, inclusive, is illustrated a slightly modified embodiment of the structures above described in which the receptacle 1' has the neck 2' provided with a spout 3'. A tubular housing 4' is seated in the neck 2' and locked therein by the spring washer 7 seated in the grooves 8' and 9'. The neck 2' is formed with the enlargement 5' providing the chamber 6'. A shell 10' is nested in the housing 4' in leak-tight engagement therewith and serves as a discharge tube. A slot 11' opens through the wall of the housing 4' to the spout 3', and a slot 12' opens through the wall of the housing 4' to the chamber 6'. A slot 13' is formed in the shell 10' to at times register with slot 11', and a slot 14' is formed in the wall of the shell 10' to at times register with the slot 12'. Slot 14' is diametrically opposite slot 13' in shell 10'. The lower end of shell 10' is closed by an integral solid portion 15 having an axially arranged threaded passageway 16' through which is threaded the stem 17'. Stem 17' is formed integral with and extends downward from the bottom 18' which in turn is integral with the side walls of the shell 10'. In this embodiment, the operating knob 19' is indicated as having the shank 19'' extending into the upper end of the shell 10' and welded thereto in the most effective available manner. Of course, the housing 4' is also preferably welded to the neck 2'. The stem 17' is provided with the thread spiral 20' having diametrically opposite longitudinal grooves 21' located to receive the spring pawl 22', one end of which is free to engage the stem 17' and the other end of which is welded into the cap 23', which cap is in turn welded or otherwise effectively anchored to the lower end of the housing 4'. A stop or knob 24' is welded or otherwise effectively anchored to the stem 17' for limiting the extent of possible upward longitudinal movement of the stem, downward longitudinal movement thereof being prohibited by the pawl 22'.

The structure seen in Figures 11 to 14 will thus be seen to be an exact embodiment of the inven-

tion as shown and described with reference to the other figures, changed only in details of construction and differing chiefly in the fact that the number of intake and discharge ports or slots for the discharge tube is varied. By virtue of the use of only a single intake and a single discharge opening 14' and 13', the lateral extent thereof can be substantially increased, as plainly seen in Figures 12 and 13, so that movement of liquid into and out of the shell 10' may be accomplished more rapidly. The bleeder port or miniature port for admitting air to the discharge tube at the time of discharge is not required in this embodiment, since the port 13' is sufficiently large to discharge the liquid and at the same time admit the required air after the manner of discharging liquid from the neck of an ordinary bottle. It will be noted also that in this embodiment only two of the grooves 21' are required to provide the necessary notches for the action of the pawl 22', since the tube 10' is turned through 180° with each movement for filling or emptying. The parts being in the position seen in Figure 11, the liquid will flow freely through the opening 14' into the discharge tube 10' when the receptacle 1' is inverted or partially inverted, and then the operator merely gives the knob 19' a sufficient turn to bring the port 13' into register with the slot 11'. This brings the port 14' to a closed position at a point diametrically opposite the slot 12', and the liquid can be discharged from the tube 10' without any further liquid escaping from the receptacle 1'.

The other parts being sufficiently nearly identical with those above described, the balance of the operation and the reasons for the constructions employed are obvious.

The modification disclosed in Figure 13 is substantially the same as that shown in Figures 1 and 2. In this case, however, the housing 4' is provided with a groove 31, preferably located diametrically opposite to the nozzle 3, to register with either of the diametrically opposite ports 32, which replace the series of ports 28 in the shell 10''. Of course, these ports 32 are arranged so as to register with the groove 31 when the shell 10'' is in liquid discharge position. Only two of the ports 14 are employed in this form of the invention; namely, the two diametrically opposite to each other and angularly displaced through 90 degrees with respect to the ports 32. Since the remaining parts of this modification are the same in every respect as the corresponding parts of Figures 1 and 2, the same reference numerals are applied to said parts.

It will, of course, be understood that reference herein and in the appended claims to the capacity of the present invention to preclude re-emptying of a container refers to the fact that the container cannot a second time be re-emptied through the natural or prepared orifice for emptying without some defect or alteration occurring or developing and becoming apparent showing the fact that the container has been re-filled.

The house 4 (or 4' or 4'') may be considered a valve casing, and the shell or measuring discharge tube 10 (or 10' or 10'') may be considered a rotary valve cooperating with its valve casing to alternately turn on and off communication with the interior of container 1 by an air-lock action, so that at no time is there direct communication from the exterior to the interior of the container, and the successive steps of intercommunication are accompanied by proportionally progressive movement of a stop that eventually terminates the possibility of further

air-lock action of the valve. The valve can not be backed or reversed in its movement because of the action of the pawl 22, and it can not be rotated in the direction of advance because of the stop 24. While it is a fact that the valve or discharge tube 10 in thus operating does actually measure, or can be caused to measure, the quantity discharged, it is not merely a measuring device. The operator, if he chooses, can discharge 10 less than a full tube 10 at any time, but if he does so, he risks not being able to completely empty the bottle for lack of sufficient opportunity for movement of the stop 24. It is not possible to discharge an amount more than one full tube 15 10 at a time. The capacity of the device, however, to thus effect a measuring action is but an incident to its further and more important capacity to preclude discharge of more than an amount equal to the containing capacity of the 20 receptacle 1. It serves both to prevent refilling and to prevent re-emptying, so that attempts at spurious filling through other avenues than the discharge port are effectively discouraged.

What I claim is:

- 25 1. The combination with a receptacle having an intake and a discharge orifice, of a valve casing fixed in said receptacle, a valve rotatable in said casing and having intake and discharge ports adapted to be brought alternately into communication with the interior of the receptacle and with the exterior thereof and located to avoid

both communications at any time, a stem projecting from said valve and screw-threaded through a portion of said casing, the stem having longitudinal grooves across the threads thereof, a pawl pivoted to the casing and resiliently stressed into engagement with the notches formed by the intersection of the threads with said grooves, and a stop at the free end of the stem, to limit the total possible movement of said valve in the direction permitted by the action of the pawl. 5 10

2. The combination with a receptacle having an intake and a discharge orifice, of a cylindrical valve casing closed at one end and fixed in said receptacle, a valve rotatably and slidably mounted in said casing and having intake and discharge ports adapted to be moved alternately into communication with the interior and exterior of the receptacle, said casing having its closed end located within the receptacle and provided with 20 an axial internally screw-threaded aperture, said valve having a screw-threaded stem engaging the threads of said aperture, and a stop at the free end of the stem to limit the total possible movement of the valve in one direction axially 25 of said casing, said stem being provided with grooves extending lengthwise thereof, a pawl pivoted in said casing, and means for holding the free end of said pawl against the grooved stem to prevent rotation of the valve in one direction. 30

LESTER L. LEWIS.
